SKYLIGHT CONSTRUCTION

George H. Lenke, Elmhurst, Ill., assignor of one-half to Julius J. Ohlis, Oak Park, Ill.

Application March 20, 1946, Serial No. 655,854

6 Claims. (Cl. 108—16)

1

This invention relates to skylights and more particularly to those having heat insulating values, having for its object to provide a construction which is more readily formed and at lesser cost than those heretofore proposed.

With these and other objects in view the invention resides in the novel details of construction and combinations of parts as will be disclosed more fully hereinafter and particularly covered by the claims.

Referring to the accompanying drawings forming a part of this specification and in which like numerals designate like parts in all the views,

Fig. 1 is a schematic representation in plan of a portion of a skylight;

Fig. 2 is a vertical sectional view through a skylight made in accordance with this invention;

Fig. 3 is a partial vertical sectional view showing a modification of the construction shown in Fig. 2;

Fig. 4 is a top plan view of a frame for supporting a hollow glass block used in the skylight construction; and

Fig. 5 is a transverse sectional view of the frame shown in Fig. 4, said view taken as on the line 5—5 thereof and looking in the direction of the arrows.

The skylight according to this invention comprises a plurality of intersecting ribs extending across the opening in the roof for the skylight, the intersecting ribs forming any desired geometric pattern, the areas defined by the intersecting ribs constituting light admitting cells, and in each cell there is fitted a hollow glass block having heat insulating values as well as the ability to transmit light rays. One of the patterns contemplated is indicated in Fig. 1 wherein the intersecting ribs are rectangularly arranged and spaced from each other so as to provide square cells for the accommodation of the square hollow blocks indicated by the numeral 2, but it is to be understood that other geometric patterns may be utilized in connection with skylight glasses of regular polygonal form other than squares.

The ribs preferably are of concrete and with reference to Fig. 2, the rib 3 is shown parallelly disposed to another rib 4, these ribs being continuous across the skylight opening with their ends supported in any convenient manner, each rib being of a vertical height slightly less than the thickness of the hollow glass blocks such as 2, the ribs preferably being reinforced as by the tie rods 5 running in one direction, and by the tie rods 6 running crosswise thereto and reinforcing

the intersecting ribs. Suitable forms are employed when pouring the concrete to form said ribs, whereby the entire rib structure is monolithic. The transverse shape of a rib may be as desired, the ribs shown in the drawings having vertical sides which are slightly tapered convergently in their upward extent.

To assist in forming or casting the ribs, as well as to serve as a support for the hollow glass blocks, there are utilized a plurality of metallic frames such as illustrated in Figs. 4 and 5, which frames are of light weight metal, preferably cast aluminum. Each frame is of a dimension and shape to conform with the cell formed by the intersecting ribs, and comprises a planar base portion 10 with a continuous upwardly extending wall portion 11 whose uppermost edge portion 12 is deflected angularly out of the plane of said wall in order to serve as an anchoring means to hold said frame to the concrete ribs, said edge portion being outwardly deflected with respect to said frame. In the preferred embodiment of this invention, interfitting and/or interlocking lugs are formed at spaced intervals along the outer edge portions of the base 10 of said frame, in Figs. 4 and 5 the male lug 13 being illustrated on one edge of the frame and a complementally formed female lug 14 being shown on the opposite edge of the frame so that, when two similarly formed frames are brought into juxtaposed relation, the complementally formed lugs will coengage and/or interlock, to the end that the outer edge 15 of the one frame will abut the opposite outer edge 16 of said juxtaposed frame. These lugs may be of any suitable formations which will coengage and/or interlock, and if desired for some installations they may be omitted, as indicated in the modification shown in Fig. 3. The base portion 10 of the frame extends in both directions from the wall portion 11, the outward extension thereof providing the abutting frame edges 15 and 16 just mentioned, and the inward extension thereof providing the flange or seat for supporting the glass block.

45 In the casting of the ribs, a suitable platform or support is provided upon which the plurality of frames are positioned with their base portions 10 resting upon said platform and their edges in abutment with each other and intersecured by the lugs 13 and 14. Then suitable substantially vertical side-boards are erected to form the ribs, said side-boards automatically being positioned by the surfaces of the upstanding walls 11 of said frames, and then the reinforcing rods 5 and 6 are positioned, after which the concrete is poured.

2

The deflected edge portions 12 of said frames will thus be embedded in the concrete and thereby anchor said frames to the ribs.

Before the concrete has set, wear resisting metallic cover strips 20, each of general T shape in transverse section, are impressed centrally of the upper extremities of the ribs, the upper flat flange portions of said strips being spaced slightly above the upper surface of the concrete rib in order to provide a space therebetween into which, ultimately, sealing compound indicated at 21 may be forced. Those strips 20, running in one direction across the skylight, are continuous from one side to the other of the skylight, but those strips such as 22 which are positioned transversely of the strips 20 are intercostal with respect to the strips 20 as indicated in Fig. 1. The upper flat flange portions of all of the cover strips are caused to lie substantially in the same plane, which plane will include the top surfaces of the glass blocks when said blocks are deposited in the light cells.

After the concrete rib structure has set, the forms are removed, and then a hollow glass block is inserted into each skylight cell defined by said ribs, said block coming to rest on and being supported by the inwardly extending flange portion 23 of the base portion 10 of the frame, and sealing compound 21 of any suitable character is pressed into the space between each block and the side surface of a rib, as well as into the space beneath the cover strips, said compound being troweled smoothly with respect to the top surfaces of the glass blocks and the said cover strips.

Thus it will be seen that by this construction there is provided a plurality of preformed coating block supporting frames which themselves constitute the bottom form upon which the concrete ribs are cast, and that the upstanding wall portions 11 of said frames serve automatically to position the side-boards which are employed as the forms for the sides of the cast concrete ribs. Further, said frames serve as spacers for centering the cast concrete ribs on prescribed centers, due to the fact that said frames are preformed in accordance with the dimensions of the light admitting cell and the block employed therein, the said upstanding wall portions 11 of the frames determining the such centering. Lastly, the frames are anchored to the ribs by virtue of the deflected upper edge portions 12 of said walls, by virtue of said edge portions being embedded in the cast ribs, and the entire skylight construction is given a substantially flush under-surface since the base portions of said frames are of relatively thin metal extending inappreciably beyond the plane of the bottom surfaces of the glass blocks supported thereby, resulting in a neat appearance. The lateral extent of the flange seats 23 for the blocks being only sufficient to support said blocks, a maximum of light transmission is provided by each cell.

It is obvious that those skilled in the art may vary the details of construction and arrangements of parts without departing from the spirit of this invention, wherefore it is desired not to be limited to the exact foregoing disclosure except as may be required by the claims.

What is claimed is:

1. In skylight construction the combination of intersecting concrete ribs defining light-transmitting cells, the bottom surfaces of said ribs lying in a common plane; a light-transmitting glass in each cell; and a metallic frame for supporting the glass in the cell, said frame anchored

5 to the contiguous ribs and provided with an outwardly extending flange underlying the bottom surfaces of said ribs, the lateral edge of said flange in abutment with the lateral edge of the flange of the next adjacent and similarly formed frame to provide a flush under-surface of the skylight parallel to said plane.

2. In skylight construction the combination of intersecting concrete ribs defining light-transmitting cells; a light-transmitting glass in each cell; and a metallic frame for each cell, each frame conforming to the shape of the cell and the glass therein and disposed at the lowermost portion of the cell, said frame having an upstanding wall portion generally disposed in the plane of a side surface of a rib, and also having an inwardly extending flange portion for supporting the glass in the cell, said frame anchored to a rib through the instrumentality of said wall, and having an outwardly extending flange underlying the bottom surfaces of the contiguous ribs.

3. In skylight construction the combination of intersecting concrete ribs defining light-transmitting cells; a light-transmitting glass in each cell; and a metallic frame disposed at the lowermost portion of the cell for supporting the glass in the cell, said frame having an upstanding wall portion generally disposed in the plane of a side surface of a rib, the edge portion of said wall being deflected and extending into the body of a rib whereby to anchor said frame to said rib, said frame also having an outwardly extending flange underlying the bottom surfaces of the contiguous ribs.

4. A frame for supporting a glass in a light-transmitting cell of a skylight, the such cell defined by concrete side members, said frame comprising a planar base portion and a wall extending upwardly therefrom, said base portion and said wall having continuous extent relative said frame, the edge portion of said wall deflected out of the plane of said wall to provide an anchoring means for said frame relative such concrete side members, the base portion comprising a section directed outwardly with respect to said frame beyond said wall and adapted to underlie the bottom surfaces of such side members.

5. A frame for supporting a glass in a light-transmitting cell of a skylight, the such cell defined by concrete side members, said frame comprising a planar base portion and a wall extending upwardly therefrom, said base portion and said wall having continuous extent relative said frame, the edge portion of said wall deflected out of the plane of said wall to provide an anchoring means for said frame relative such concrete side members, the base portion comprising one section directed inwardly of said frame from said wall to provide a seat for the glass, and comprising another section directed outwardly of said frame from said wall to underlie the bottom surfaces of such side members, the outer edge of the outwardly directed section of said base portion on opposite sides of the frame having complementarily formed members adapted to interfit with similarly formed members of an adjacent frame.

6. A frame for supporting a glass in a light-transmitting cell of a skylight, the such cell defined by concrete side members, said frame comprising a planar base portion and a wall extending upwardly therefrom, said base portion and said wall having continuous extent relative said frame, the edge portion of said wall deflected out of the plane of said wall to provide an anchoring means

for said frame relative such concrete side members, the base portion extended inwardly of said frame beyond said wall to provide a seat for the glass, the outer edge of said base portion on opposite sides of the frame having complementally formed members adapted to interfit with similarly formed members of an adjacent frame.
